RADIO-FREQUENCY CONTACTOR

Joseph F. Frese, Baltimore, Md., assignor to The
Monitor Controller Company, Baltimore, Md.,
a corporation of Maryland

Application November 7, 1945, Serial No. 627,229

5 Claims. (Cl. 200—153)

1

My invention relates broadly to high frequency contactors and more particularly to a quick acting high voltage radio frequency contactor system.

One of the objects of my invention is to provide a construction of high voltage high frequency switching system in which high frequency contactors may be controlled by a magnetic actuator disposed in a position substantially removed from the high frequency contactors.

Another object of my invention is to provide a construction of high frequency contactor system in which a removable switch element is pivotally mounted with respect to opposed spaced contactors for operation between the opposed contactors under control of a spring device in one position and under control of a magnetic actuator in another position.

Still another object of my invention is to provide construction of a high frequency contactor in which a high frequency switch element is pivotally mounted for movement between fixed contactors in which the switch element occupies a position in abutment with one of the contactors under positive spring tension and is operative to establish connection with an opposed contactor by longitudinal movement of a member controlled by a magnetic actuator substantially removed from the area of the high frequency contactors.

Another object of my invention is to provide a construction of high voltage high frequency switching system in which a relatively short stroke magnetic actuator produces a magnified movement of a movable contactor arm with reference to coacting contact members.

A further object of my invention resides in a construction of high frequency contactor operative under control of a relatively short stroke magnetic actuator as set forth more fully in the specification hereinafter following by reference to the accompanying drawings in which:

Figure 1 is a front elevational view showing the high frequency contactor of my invention; Fig. 2 is a side elevational view of the high frequency contactor illustrating the switch element of the contactor moved to one of its limiting positions under positive spring control; Fig. 3 is a view similar to the view illustrated in Fig. 2 but showing the switch element positively operated under control of the magnetic actuator in the other of its limiting positions; Fig. 4 is a horizontal sectional view taken substantially on line 4—4 of Fig. 2 and illustrating the very substantial insulation which is provided for mounting the high

2

frequency contactors of the switch system of my invention; and Fig. 5 is a horizontal sectional view taken substantially on line 5—5 of Fig. 2.

My invention provides a simplified construction of high frequency contactor particularly intended for radio frequency operation where the contactor system is substantially removed or spaced from the magnetic actuator employed for operating the contactor system. I provide an arrangement by which a radio frequency circuit established through a switch element and contactor may be broken under conditions of very slight movement and a radio frequency circuit established between the switch element and an opposed radio frequency contactor. The switch element in the system of my invention is normally biased by spring means to a closed position with respect to a radio frequency contactor and is subject to displacement by a short stroke magnetic actuator to a position establishing a circuit connection with an opposed contactor. The magnetic actuator is so far removed from the radio frequency contactor system that no detrimental losses between the high frequency operating circuits and the low frequency actuator circuit can occur.

Referring to the drawings in more detail reference character 1 represents a vertically disposed panel structure of insulation material supporting adjacent the top thereof the pedestal insulator 2. The insulator 2 is centrally recessed and screw threaded at the end 2a thereof and is engaged by the screw 3 which passes through the panel 1 and engages the screw threads 2a in pedestal insulator 2. The other end of pedestal insulator 2 is recessed and screw threaded as represented at 2b for the passage of the screw 4 which extends through the insulated panel structure 5 in spaced relation to panel structure 1. The pedestal insulator 2 is precluded from twisting with respect to insulated panel structure 1 by means of a pin 6 which passes through the panel structure 1 and enters a recess in the end of pedestal insulator 2. The panel 5 is prevented from twisting or shifting with respect to pedestal insulator 2 by reason of pin 7 which passes through panel structure 5 and is embedded in the end of pedestal insulator 2.

The panel 5 of insulation material serves as a support for a pair of spaced radio frequency contactors represented at 8 and 9. The radio frequency contactors 8 and 9 are each provided with a silver contact surface represented at 8a and 9a respectively, and a screw threaded shank shown at 8b and 9b. The screw threaded shanks 8b and 9b extend through the panel 5 and are

engaged by sets of nuts and washer elements including nuts 8c and 8d and washer element 8e and 8f; and nuts 9c and 9d coacting with washer elements 9e and 9f for adjustably supporting the contacts 8 and 9 with respect to panel 5.

The adjustable mounting of contacts 8 and 9 is very important as the stroke of the actuator and the angular movement of the switch element can thereby be regulated to insure proper opening and simultaneous make or break of the radio frequency contactor system as will be hereinafter pointed out in more detail.

In positions opposite the contactors 8 and 9 on panel 5, I mount fixed radio frequency contactors 10 and 11 on panel 1. Contactors 10 and 11 are each provided with silver facings 10a and 11a and have screw threaded shanks 10b and 11b extending therefrom and passing through insulated panel structure 1. The screw threaded shanks 10b and 11b have washer members 10e-10f and 11e-11f secured thereon with nuts 10d and 11d engaged over the screw threads of the shanks. Thus, radio frequency connections may be made through lugs engaged between the washer members 10e-10f and 11e-11f to contactors 10 and 11 and radio frequency connections established to the adjustable contactors 8 and 9 through lugs secured between washer elements 8e-8f and 9e-9f.

The switch element of the radio frequency contactor system is mounted intermediate the contactors hereinbefore described. I mount a metallic standard 12 on the insulated panel structure 1 and secure the standard thereto by means of a shank 12a which passes through the panel structure 1, with screw threads 12b thereon which are engaged by nuts 12c and 12d and coacting washer members 12e and 12f. Radio frequency energy may be supplied to standard 12 through a suitable lug disposed between washer members 12e and 12f and secured by nuts 12c and 12d. The standard 12 serves as a pivot means at 14 for journaling the angularly shiftable bifurcated member 15 which is substantially quadrantal in shape and serves as a support adjacent one end thereof for the switch element 16 and at the other end thereof serves as a support for the roller member 17. The roller member 17 is mounted to revolve about axis 17a as the contact operating bar 18 of the magnetic actuator 19 establishes engagement therewith as represented in Fig. 3. The switch element 16 is formed from striplike resilient material such as bronze or beryllium copper having a very substantial strength and resilience. The switch element 16 is substantially Y shaped at the end thereof as represented at 20 and terminates in contacts 21 and 22 which are disposed at obtuse angles with respect to the branches of the Y. Contacts 21 and 22 are thus supported in positions whereby the contact faces thereof shown at 21a and 22a establish abutting contact with the contactors 9 and 11 in the two extreme positions of the switch. At the supported end of the switch element 16 carried by the angularly shiftable bifurcated member 15 I provide a flexibly braided conductor 23 which provides a positive connection from the end of the switch element to the binding post 24 on standard 12, thus eliminating any losses which might otherwise occur through the pivotal connection of the switch arm.

I arrange a symmetrically disposed switch arm 25 on a separate standard 26 similar to standard 12 but spaced therefrom transversely of the panel 1, aligning contacts carried by switch arm 25

with opposed contacts 8 and 9. A bifurcated supporting member 27 pivotally mounted at 28 on standard 26 is arranged in a manner similar to the arrangement of bifurcated member 15 and its relation thereto on standard 12. A roller 29 is pivotally mounted on bifurcated supporting member 27 in a manner similar to the arrangement of roller 17. Rollers 17 and 29 may thus be engaged by the contact operating bar 18.

The contact operating bar 18 is substantially trapezoidal in shape and is formed from insulation material with the broad face thereof shown at 18a, engageable with roller members 17 and 29. The narrowest face 18b thereof is clamped by bolt members 20 which pass through the longitudinally extending links 30 and 31 and through the spacer blocks 32 and 33 for centrally supporting the bar 18 in a position directly aligned with rollers 17 and 29. The links 30 and 31 extend adjacent the magnetic core structure 34 of the magnetic actuator 19 and are secured to the armature 35 thereof. The magnetic core structure 34 has an operating winding 36 associated therewith connected to terminals 37 and 38 supported on a suitable strip of insulation material represented at 39. An electrical circuit may thus be established to the operating system of the magnetic actuator.

The core structure 34 is supported with spaced relation to the insulated panel 1 by means of the spacer 40 and bracket members 41 with coacting fastening screws 42 and 43 associated therewith.

The magnetic contactor is so aligned with the pivotally mounted quadrantal bifurcated members 15 and 27 that an operating force may be presented directly against roller members 17 and 29 in an upward direction. Because of the eccentric mounting of the switch element 16 with respect to the position of force application from operating bar 18, the switch element 16 is forced from the position in which it is yieldably maintained by coil spring 44, as shown in Fig. 2, to the position shown in Fig. 3. Thus, a quick change of circuit connections may be effected from contactors 8 and 9 through switch arms 16 and 25 to the contactors 10 and 11. The position of the switch illustrated in Fig. 3 is maintained so long as the magnetic actuator 19 is energized. As soon as magnetic actuator 19 is de-energized the operating bar 18 drops gravitationally from the bifurcated members 15 and 27. The bifurcated members 15 and 27 are returned to a position in which arms 16 and 25 are positively shifted by spring members shown at 44.

The tension springs 44 are positioned so that one end enters the standard 12 or 26 while the other end bears against the bifurcated member 15 or 27 that carries arm 16 or 25 with the coiled intermediate portion thereof enveloping the stud 14 or 28. This arrangement serves to wholly shield the spring 44 as the convolutions and the opposite ends thereof are disposed between the side portions of the bifurcated members 15 or 27. The shielding is complete because the end of the spring 44 at one end enters a socket in the end of the standards 12 or 26 while the opposite end of the spring is engaged behind the bifurcated member 15 or 27. Corona is not likely to occur around the tension spring due to shielding action of the bifurcated members.

The magnetic actuator is substantially removed from the radio frequency contactors and does not offer any problems with respect to capacity or interference with the high frequency circuits confined to the radio frequency contactors.

While I have described my invention in one of its preferred embodiments, I realize that modifications may be made and I intend no limitations upon my invention other than may be imposed by the scope of the appended claims.

While I claim as new and desire to secure by Letters Patent of the United States is as follows:

1. A high frequency switch comprising a vertically extending support of insulation material, a pair of horizontally extending standards projecting from said support, a bifurcated member individual to each of said supports and journaled with respect thereto, a switch arm carried by each of said bifurcated members, a pair of contacts carried by each of said switch arms, opposed substantially aligned stationary coplanar contactors arranged in a plane substantially normal to the plane of said vertically extending support at opposite limits of travel of the contacts carried by said switch arms, springs interposed between said standards and each of said bifurcated members for continuously urging said switch arms to a position in which one of the contacts thereof establishes connection with the associated aligned coplanar contactor and pusher means operative linearly in a plane substantially normal to the planes of said coplanar contactors for simultaneously displacing said switch arms in an angular direction to establish connection between the others of the contacts carried thereby and the others of said coplanar contactors in opposition to the action of said springs which normally maintain engagement between the first mentioned contacts carried by said switch arms and the first mentioned aligned coplanar contactors.

2. A high frequency switch comprising a support of insulation material, a pedestal insulator extending in a substantially horizontal plane with respect to said support, a panel of insulation material carried by one end of said pedestal insulator, a pair of contactors, one of said contactors being mounted on said support, and the other of said contactors being mounted on said panel in substantial coplanar alignment with said first-mentioned contactor, a switch arm mounting means carried by said support substantially below said coplanar contactors, a switch arm pivoted in said switch arm mounting means, contacts carried by the extremity of said switch arm and alternately connectible with either of the aforesaid coplanar contactors, a biasing spring associated with said switch arm for normally maintaining one of the contacts on said switch arm in electrical connection with one of said coplanar contactors, and pusher means spacially disposed below said coplanar contactors and operative linearly in a plane substantially normal to the plane of said coplanar contactors and substantially in alignment with one of said contactors for mechanically rocking said switch arm for moving said switch arm to a position in which the other of the contacts carried thereby establishes electrical connection with the other of said coplanar contactors.

3. A high frequency switch comprising a support of insulation material, a pedestal insulator extending in a substantially horizontal plane with respect to said support, a panel of insulation material carried by one end of said pedestal insulator, a pair of contactors, one of said contactors being mounted on said support, and the other of said contactors being mounted on said panel in substantial coplanar alignment with said first-mentioned contactor, a switch arm mount-

ing means carried by said support substantially below said coplanar contactors, a switch arm pivoted in said switch arm mounting means, contacts carried by the extremity of said switch arm and alternately connectible with either of the aforesaid contactors, a biasing spring associated with said switch arm for normally maintaining one of the contacts on said switch arm in electrical connection with one of said coplanar contactors, and pusher means remotely disposed below said coplanar contactors and operative linearly in a plane substantially normal to the plane of said coplanar contactors and substantially in alignment with one of said contactors for mechanically displacing said switch arm for moving said switch arm to a position in which the other of the contacts carried thereby establishes electrical connection with the other of said coplanar contactors.

20 4. A high frequency switch comprising a support of insulation material, a pedestal insulator extending in a substantially horizontal plane with respect to said support, a panel of insulation material carried by one end of said pedestal insulator, a pair of contactors, one of said contactors being mounted on said support, and the other of said contactors being mounted on said panel in substantial coplanar alignment with said first-mentioned contactor, a switch arm mounting means carried by said support substantially below said contactors, a switch arm pivoted in said switch arm mounting means, contacts carried by the extremity of said switch arm and alternately connectible with either of the aforesaid coplanar contactors, resilient tension means and a roller member associated with said switch arm, and pusher means operative linearly in a plane substantially normal to the plane of said coplanar contactors and substantially in alignment with one of said contactors engageable with said roller member for shifting said switch arm against the action of said resilient tension means from a position in which one of the contacts thereof establishes maintained connection with one of said coplanar contactors to a position in which the other of the contacts thereof establishes connection with the other of said coplanar contactors.

40 5. A high frequency switch comprising a support of insulation material, mounting means of insulation material extending substantially normal to said support, one pair of contactors disposed in aligned positions in substantially the same vertical plane on said support and another pair of contactors disposed on said mounting means in a plane substantially parallel to the vertical plane of said first mentioned pair of contactors, switch arm mounting means carried on said support in a position below said aforementioned mounting means, quadrantal members journaled on said last-mentioned mounting means substantially in alignment with planes normal to said support and coplanar with a contactor in each of said pairs of contactors, a roller carried by each of said quadrantal members in a position eccentric to the journal thereof, switch arms carried by each of said quadrantal members in a position remote from the associated roller, a pair of contacts carried by the extremity of each of said switch arms and movable in a plane between the limits of travel imposed by contactors in each of said pairs of contactors for establishing alternate connection between the contacts carried by said switch arms and said contactors, and means operative in a linear direc-

tion in a plane substantially normal to the planes of said contactors engageable with said rollers for shifting said quadrantal members from one limiting position to another.
